CARRIER DISPATCH SYSTEM

Harold F. Wilder, Chatham, N. J., and Hakon H. Haglund, New York, N. Y., assignors to The Western Union Telegraph Company, New York, N. Y., a corporation of New York

Application January 8, 1932, Serial No. 585,556

30 Claims. (Cl. 243—16)

This invention relates to carrier dispatch systems and more particularly to systems employing carrier guideways having one or more points or branches therealong at which carriers are diverted or discharged from the guideway.

An object of this invention is to provide means operated by the carriers as they travel along the guideway to cause a carrier to be discharged from the guideway at a predetermined point or branch therealong. Another object is to provide an arrangement which will operate automatically and effectively when the carriers are traveling at high speeds along the guideways. According to this invention the dispatch system may embody guideways comprising pneumatic tubes and cylindrical carriers for traveling in the tubes. It should be borne in mind, however, that the principles of this invention are applicable to any type of carrier system. Means are provided along the tubes associated with openings in the tubes or branches joined to the tubes, for causing carriers to be selectively diverted from the guideway into the discharge opening or to the branch tube. Means are provided on the carriers for selectively operating the deflector or discharge means corresponding to the point or branch at which the carrier is designated to be discharged.

By utilizing the above arrangement a carrier system may be developed which employs a main or feeding guideway of any desired extent, having a plurality of branch guideways leading therefrom with the branches having also other branches leading from them, if desired. The main guideway or a pneumatic tube may extend from a main office, such as a central telegraph office, to a distant branch office with the branch guideways leading to branch offices lying in between the main and distant office. In this manner, by the selection of the proper carrier, a message may be sent to any of the branch offices at the discretion of the operator.

Where pneumatic tube carriers are employed for conveying messages between offices separated by a substantial distance, it is the usual practice to operate the carriers at a substantially high speed, up to approximately 2400 feet per minute. At such speeds it is extremely difficult to devise mechanisms which are mechanically engaged by the carriers for operating the discharge or switching mechanism employed in connection with the various branches.

It has been proposed to utilize electric discharge tubes as relays in the place of mechanical relays operated by actual contact with the carriers. The electrical relays may be operated by

means impressing a potential thereon set up when the carrier passes a certain point along the guideway. Even in this case, the duration of such potential is ordinarily only a few microseconds, which is insufficient to cause the ordinary type of electronic discharge device to operate connected mechanical devices. It is proposed, according to this invention, to employ a special type of electronic discharge tube having what is known as a trigger operating characteristic, which will respond to potential of short duration, such as are obtained with high speed operations. By trigger operating characteristic is meant a device which when set into operation will continue in operation independent of the initiating force.

Another object of this invention is, therefore, to provide a carrier dispatch system with relay devices for controlling the switching or deflecting mechanism provided at the branches which have what is known as trigger operating characteristics and which will respond to potentials of extremely short duration.

Another object of this invention is to provide a system of the character described, having a switch or deflecting device at the entrance of the branches of the guide discharge tubes, having trigger operating characteristics for moving the deflector into operating position as the carrier passes one point along the guideway and out of deflecting position when the carrier passes another point along the guideway.

A still further object of this invention is to provide a system of the character just described in which the mechanisms set into operation by the carriers are located entirely externally of the carrier tube or guideway.

It has been found in connection with the type of control mechanism described above, that the electronic discharge tubes operate most effectively when subjected to a single impulse as the carrier passes the control point. To this end a selectively responsive mechanism which will supply only a single impulse has been devised. Such a mechanism comprises a magnet arranged with its poles spaced longitudinally of the guideway and inductances in the field of the magnet for picking up current induced by the magnets as they are effected by operating means carried on the carriers in the form of armatures of magnetic material, which bridge the poles of the magnet as the carrier passes the same. Selective operation is provided by employing magnets with their poles spaced at different distances and with armatures on the carriers of a predetermined length corre-

sponding to the spacing of the poles of the magnet which the carrier is designated to influence. With this arrangement, if the magnets with the wider spacings are arranged nearest the starting point or entrance of the main guideway and arranged progressively closer together with the direction of travel, those carriers designated for points beyond the first branch will not completely bridge any of the magnets until it has reached the magnet with pole spacing corresponding to the length of the armature on the carrier.

A still further object of this invention, therefore, is to provide for selectively applying an operating potential to the electronic relay devices by employing magnets having their poles spaced longitudinally of the guideways and spaced at different distances at the respective branches.

These and other objects will be apparent from the following description and claims taken in combination with the accompanying drawings forming a part of this application in which:

Fig. 1 is a diagrammatic view of a part of a system showing one branch leading from the guideway;

Fig. 2 is a detailed view of the arrangement of the relay energizing magnet shown in Fig. 1;

Fig. 3 is a detailed view of a carrier provided with a single magnetic band thereon;

Fig. 4 is a diagrammatic view showing an arrangement employing a carrier with two spaced bands on the carrier and magnets correspondingly spaced on the guideway arranged to operate the discharge tubes arranged with their output circuits in series;

Fig. 5 is a view showing the discharge tubes provided with two types of quenching circuits and means to switch from one circuit to the other;

Fig. 6 is a diagrammatic illustration showing two branches leading from the guideway and provided with selective controlling magnets arranged with their poles disposed longitudinally of the guideway and spaced at different distances;

Fig. 7 shows the magnets provided with poles terminating in the form of a loop or ring surrounding the carrier;

Fig. 8 is a view illustrating the method of magnetically coupling the spaced bands on the carriers; and

Figs. 9 and 10 are views illustrating an arrangement employing a single magnet for selective control.

Referring to Figs. 1 to 3 of the drawings a part of a system employing the simplest embodiment of the invention is shown. A pneumatic conveyor tube 10 is provided with an inlet terminal 11 and a source of air pressure 12. Only one branch station is illustrated. It is provided by a branch tube 13 leading from the main tube and having an outlet terminal 14. An inlet terminal 15 into the main tube may be provided at the branch station for sending to stations located beyond the first branch. Carriers of the type such as carrier 16 shown in Fig. 3 are employed in this system.

The branch tube 13 is connected with the main tube 10 through a special coupling member 17 which houses a deflector or switching member 18 pivoted at its lower end and arranged to assume either one of two positions. One of these positions is before the opening leading into the branch tube and the other is across the path of the main tube. In the former position the entrance to the branch tube is cut off and carriers passing through the coupling section 17 are continued along the main tube, while in the latter position

the path of the main tube is cut off and carriers are diverted therefrom into the branch tube. The operating solenoid 19, provided with a movable core and connected to the switch operating arm 21, controls the movements of the switch.

In order to provide for selectively operating the switching mechanism, designating means is placed on the carrier or carriers intended to be sent to the branch station. Means responsive to the designating means on the carrier is provided for causing the switch to be moved into position across the path of the main tube when carriers designated for the branch station are sent through the system. According to this invention, the conveyor tube 10 or a section thereof in advance of the branch tube switch is made of a non-magnetic material and a magnet 22 is disposed at a certain point along this section in advance of the switch member 18 and arranged with its poles at opposite sides of the conveyor tube 10 substantially as shown in Fig. 2. This magnet is arranged to operate a relay mechanism which controls the operating solenoid 19. The magnet may be a permanent magnet or an electromagnet energized by coils 23 connected through the lead wires 24 to a source of potential. With either type of magnet, pick-up coils 25 are provided which are connected through wires 26 to the relay. A detecting magnet is caused to respond to the passage of a carrier by the point along the guideway, between the oppositely disposed poles by providing a band or ring of magnetic material 27 on the carrier. This ring forms a bridging member or armature between the poles of the magnet, changing momentarily the reluctance of the magnetic circuit, causing a potential to be induced in the pick-up coils 25 which may be employed to operate the relay.

When carrier speeds of from 1200 to 2400 feet per minute are employed, such as are required to meet the requirements of modern rapid service, it will be seen that a band on a carrier of a width substantially equivalent to the width of the pole faces, which it will be assumed for example is one inch, will pass between the poles of the magnet in from two to four thousandths of a second. It will be readily appreciated that this is quite too short for effectively operating the present types of mechanical relays. Moreover, with a variation in a magnetic field of such a short duration it is quite difficult to obtain therefrom an induced current pulsation of sufficient length to operate a mechanical relay. Ordinary vacuum tube relays have been proposed for overcoming the limitations of the weak impulses but here again the vacuum tube relays must operate a mechanical relay for controlling the switching device and the combined system is subject to the same time limitations as direct mechanical relay action.

However, successful operation of a system in which the carriers travel at high speed is made possible by employing a special type of electronic discharge device having what is known as trigger operating characteristics such as the so-called arc or gaseous discharge tubes which are capable of passing the requisite amount of current for operating the switching device and may be controlled by a relatively small amount of current. This tube is characterized by the fact that it normally interposes a higher resistance in the circuit in which it is connected, which resistance may be broken down by a relatively small current in the auxiliary or control circuit. Such tubes are now well known in the art and briefly consist

of a gas filled envelope which contains an electron emitting cathode, a surrounding grid and anode. The geometry of the tube, nature and pressure of the gas and electron emissivity of the cathode are such that, with the proper positive potential applied to the anode, the grid being negative will interpose a high starting resistance to the tube but if the grid is rendered positive by suitable potential the tube will break down and, 10 due to the arc discharge then occurring, will allow a large amount of current to flow from the anode to the cathode.

The tube is unlike the ordinary three element vacuum tube or audion in that as soon as an anode current starts the grid has no further influence on the anode current and the discharge can be stopped only by removing the anode voltage or reducing it to the extinguishing point. The action of the grid may, therefore, be likened 20 to a trigger and the term "trigger action or trigger operating characteristic" as used herein is employed to designate any type of electronic discharge device operating in the above manner.

In the embodiment of the invention above described an electronic discharge tube 27 is arranged to supply the operating current to the switch operating solenoid. The tube is provided with a cathode 28 heated from a suitable source of current, a starting grid 29 and an anode 31. 30 The pick-up coils 25 are connected through the lead wires 26 in the circuit of the control grid 29. The anode is connected through wire 32 in series with the operating solenoid 19 and a circuit interrupting switch 33 to a source of positive potential. When a carrier 16 having a band of magnetic material thereon is inserted into the carrier tube 10 it will proceed until it passes the position of the magnet 22 where it will cause the fluctuation in the magnetic field, inducing surge 35 of potential in the pick-up coils 25 and the circuit including the grid 29. The grid is ordinarily maintained at a slightly negative potential. The induced current impulse will cause a positive potential to be impressed upon the grid 29 and due 40 to its trigger operating characteristic the tube will break down and space current will flow from the cathode to the anode. When this occurs the solenoid will be energized and the switch mechanism immediately swung over into the path of the main tube. The detecting magnet is positioned sufficiently ahead of the switch mechanism to permit the switch to move to its deflecting position before the arrival of a carrier. When the carrier enters the branch tube 13 it will engage 45 a cam 34 raising the same and opening the switch 33. This will interrupt the anode circuit and cause the resistance of the tube to be restored, or in other words, allow deionization to occur.

Besides operating a switching mechanism the 50 arrangement just described may be employed for counting carriers or other objects which pass a certain point along a guideway. Other uses may be made of the arrangement for detecting the number of objects of or containing magnet material which pass a certain point.

When a carrier having only one ring or band 55 of magnetic material is employed, the selection is limited to one of two destinations. This would restrict the system to a main tube with a sending 60 station and a station at the remote end thereof and one intermediate branch station. To transmit a message or other article to the remote station, at the end of the main tube a carrier having no band would be employed, in order that the 65 magnetic circuit in advance of the branch station

would not be affected by the passage of the carrier designated for the remote station. When it is desired to transmit to the branch station a carrier having a magnetic band thereon would be employed. As this carrier passes through the magnetic field between the poles of the magnet it will modify the field, thereby setting in operation the devices which cause it to be diverted into the branch tube in the manner already described.

If it is desired to provide a system permitting 10 the carriers to be sent to more than two destinations, this may be accomplished by employing in addition to the single band carriers, other carriers with two or more bands of magnetic material spaced a suitable distance apart longitudinally of the carrier. The number of stations which can be added to the system will be determined by the number of carrier bands which may be employed spaced at the minimum affective distance apart. At the station for which a carrier 15 provided with a specific number of bands is destined, a corresponding number of magnets will be placed along the conveyor to be spaced apart at distances corresponding to the bands on the carrier. 20

Referring to Fig. 4 an arrangement is illustrated in which a carrier employing two bands is utilized. The carrier 16 is supplied with bands 35 and 36 surrounding the central portion of the carrier and spaced longitudinally thereof. A pair 30 of magnets 37 and 38 are arranged with their poles on opposite sides of the carrier tube substantially as shown in Fig. 2, and are spaced apart longitudinally of the tube at a distance corresponding to the spacing of the bands on the carrier. 35 The magnets may be of substantially the same form as those illustrated in connection with the foregoing embodiment. These magnets are arranged to energize two electronic discharge tubes by being coupled in the grid circuit of the 40 tubes in substantially the same manner as where a single magnet and a single tube are employed. The grid of each tube is coupled to its corresponding magnet so as to be subjected to the potential induced by the modification of the magnetic fields as the carrier bands pass therethrough. 45 It will be observed that as the carrier passes the magnets the leading band 35 will first pass through the field of the magnet 37 and subsequently through the field of the magnet 38. The 50 band 36 will pass through the fields in like order. However, it will be observed that the fields will be simultaneously modified only when the leading band 35 is passing through the field of the magnet 38, coincidentally with the passage of the following band 36 through the magnet 37. 55

With a multiple band carrier arrangement the relay tubes could be connected to an operating solenoid of such a character that only the total effect of all of the tubes operating simultaneously 60 would cause the solenoid to respond. However, according to this invention, a more effective method is employed. Instead of the output circuits of the tubes being connected in multiple with the solenoid they are connected in series. In 65 other words, in this arrangement the grids 41 and 42 of the relay tubes 43 and 44 respectively are connected independently or parallel with the magnetic pick-up coils while the anodes 45 and 46 of the respective tubes are connected in series. 70 That is, the path of the current through the tubes would be from the cathode 40 of the first tube 43 to the anode 45 thereof, thence to the cathode 41 of the tube 44 to the anode 46 thereof, and thence through the output circuit 48 and the operating 75

solenoid 49 in series therewith and to a source of positive potential. In this arrangement it will be observed that the relay tube 44 is at some intermediate potential rather than at the same potential as the tube 43, and as a result the cathode of the tube must likewise be maintained at some intermediate potential. This may be provided for by the insertion of a battery 51 between the source of negative potential and the cathode. 10 This arrangement likewise provides the required positive potential for the anode of the first tube 43.

With the relay tubes in series due to the natural high resistance of the tubes before they are triggered off, the starting of either one of the tubes alone will not start the other tube and therefore the output circuit will not be completed. 15 The completion of the output circuit can be accomplished only when both of the tubes are started at the same time by a simultaneous application of the required starting potential to the grids of the respective tubes.

With an arrangement such as just described it will be seen that three or four or any other 25 suitable number of tubes may be arranged in series and excited by the corresponding number of magnetic fields placed along the carrier tube to be simultaneously excited by magnetic bands on the carriers. This would provide for an additional station for each group of tubes used, increased in arithmetical series. In addition to providing for selective discharge of the carriers by the number of carrier bands and magnetic fields employed, this arrangement may be made selective 30 by a different spacing of the bands along the carrier. If the bands are spaced differently it is obvious that simultaneous potentials will be impressed on the grids of the tubes only when the carrier passes a group of fields spaced at the same 40 distance as the bands on the carrier.

In the embodiment first described the switching device for diverting the carriers at the intermediate or branch stations was restored to normal by means operated by mechanical contact 45 with the carriers. Although the interruption of a circuit can be more readily accomplished by operations of an extremely short duration than the completing of a circuit, any type of mechanical engagement with the carrier subjects the 50 engaging parts to a substantial amount of wear and tear and introduces the possibility of the carriers becoming jammed in the guideway. To overcome this difficulty it is proposed according to this invention to employ magnetic or like 55 means which the carrier may operate without mechanical contact substantially in the same manner as employed in connection with the circuit initiating the movement of the switching means. Referring to Fig. 5 such an arrangement is provided by employing a magnet 52 along the branch tube 13 instead of the cam operated switch 33 (shown in Fig. 1). The switching mechanism 18 is usually biased toward one of its extreme positions and in the embodiment first 60 described it is biased toward the position over the entrance of the branch tube. Therefore, after the switch has been moved across the path of the relay it is only necessary to deenergize the relay to permit the switch to return to its normal position. Therefore, when a magnet is employed for 65 restoring purposes the relay may be deenergized by employing an arrangement which will cause the discharge tube to be quenched in response to

the passage of the carrier through the field of the restoring magnet.

The arrangement shown in Fig. 5 providing for this comprises two relay tubes 53 and 54 arranged to be started by the magnet 22 ahead of the switching device and the magnet 52 in the branch tube respectively. The two relay tubes are arranged to operate in a connected circuit by means of which the tubes are mutually quenching. In other words, one of the tubes being in 10 operation, it is extinguished or quenched by action set up by the other as soon as it has started. Such an arrangement is described in the proceedings of the National Academy of Sciences, March, 1921, vol. 15, No. 3, page 218. The tube 53 is arranged so that when a current is induced into the grid circuit as a carrier passes between the poles of the magnet along the guideway 10, a starting impulse will be impressed upon the grid 55 of the relay tube. The required positive potential for 15 the anode 56 of this tube is supplied through the wire 57 which includes in series therewith the switch operating solenoid 19 and one side of the bi-polar changeover switch 58. The grid circuit of the other relay tube 54 includes the pick-up 20 coils 62 of the magnet 52, which provides for similarly impressing a starting potential on the grid 59 when the carrier passes said magnet in its travel through the branch tube 13. Positive potential is supplied to the anode 63 of the latter 25 relay tube through the wire 64 and the other side of the changeover switch 58. A resistance 65 may be included in this circuit to supply a balancing load in the output circuit of the latter 30 relay tube. The anode circuits of the tubes are 35 bridged by a condenser 66.

When a carrier passes the detecting magnet 22 the switch will be moved into the diverting position and at the same time the condenser 66 will 40 will be charged from tube 53. As the carrier passes the diverting switch into the branch tube and reaches the restoring magnet 52, the other relay tube 54 will be started whereupon the condenser 66 which was previously charged from the tube 53 will now be subjected to current in a reverse 45 direction, and therefore discharges in such a direction as to momentarily reduce the voltage in the anode circuit of the tube 53 sufficiently to interrupt the discharge extinguishing this tube.

While the changeover switch 58 is connected in its upward position the tube 54 will continue in operation until it is in like manner extinguished by the starting of tube 53, which occurs when the next carrier arrives having magnetic material thereon. When this tube starts 55 it will subject the condenser 66 to another pulsation of current in a direction the reverse of the current last impressed. This will likewise act to momentarily reduce the voltage in the anode circuit of the tube 54 sufficiently to interrupt the 60 discharge through this tube.

From the above it will be seen that when one tube is started it remains in operation until the other tube is started when it is quenched remaining out of operation until it is again started by the passage of a carrier. This arrangement is very satisfactory where the carriers pass at fairly frequent intervals. However, if the interval of arrival of carriers is substantially extended, which may readily occur during certain 70 periods of operation, it would not be economical to operate the mechanism in the above manner because one of the tubes would be drawing current during extended periods of inactivity. During such intervals it is obvious that the tube 54, 75

controlled by the restoring magnet 52, will be the one continued in operation. To obviate this automatic extinguishing means have been provided to act upon this tube as soon as the tube 53 has been quenched. Such an arrangement is provided by the circuit connections made when the changeover switch 58 is moved to its lower position. In this position the anode circuit of the tube 53 is connected with the operating solenoid 19 through wire 67 and the windings of the relay 68. The anode circuit of the tube 54 is connected through the switch in this position through the tongue of this relay to the wire 64 leading to source of positive potential. This connection is made through back contact of the relay and the tongue is biased toward an open position by means of a spring 69.

When the circuits are connected through the switch 58 in its lower position the starting of tube 53 will cause the relay 68 to close the anode circuit of the tube 54 through its back contact. As soon as the tube 54 is started it will quench or extinguish the other tube in a manner already described and as soon as current has ceased to flow through its anode circuit and the relay 68 the tongue will drop away and immediately open the anode circuit of the tube 54 automatically extinguishing the same. This operation will be repeated for each carrier to which the system responds.

Referring now to Figs. 6, 7 and 8, another embodiment of this invention is illustrated which provides for selective response of the deflector switch operating mechanisms, by employing magnets having their opposite poles spaced longitudinally along the carrier tube or guideway at correspondingly different distances apart at each branch leading from the guideway. This arrangement requires fewer parts than that employing a plurality of magnetic fields with a plurality of relay tubes operating in series arrangement, as described in connection with the embodiment illustrated in Figs. 1 to 3. This arrangement requires the use of only one magnet and one electronic device or relay tube in connection with the control mechanism at each branch. A magnet such as the magnet 70 or 71 is disposed in advance of each branch or discharge point along the guideway with the poles 72 and 73 thereof spaced longitudinally of the tube or guideway 10. The magnets may be either a permanent magnet or an electro-magnet supplied with an exciting current through coils 23 from a suitable source. It is provided with pick-up coils 25 similar to the magnets employed in the foregoing embodiments. The pick-up coils are connected in the grid circuit of a relay tube 74 shown at only one of the branches. The anode circuit of the tube is supplied with a positive potential through a wire 75 including the switch operating solenoid 19 and the interrupting switch 33. The operation of the relay and anode circuit when the required potential is impressed on the grid, will be apparent from the description of the foregoing embodiment.

With the poles of the magnet arranged in spaced relation longitudinally of the guideway, it will be apparent that the magnetic circuit instead of extending transversely of the guideway, as in the foregoing embodiment now extends longitudinally of the guideway. In order that the poles of the magnet may be bridged to modify the field when a carrier passes the poles the carrier is now provided with bands spaced at a distance corresponding to the poles of the mag-

net and coupled with a suitable bar of magnetic material. A carrier of this type is illustrated in Fig. 8 and embodies bands 76, 77 coupled by a bar 78 of magnetic material 79. When the carrier bands arrive at a magnet having its poles spaced at substantially the same distance as the bands on the carrier, the flux of the magnetic circuit flows into the rings and through the bar coupling the two rings to complete its circuit. In other words, the rings and coupling bar form an armature which momentarily reduces the reluctance of the magnetic circuit as the rings on the carrier arrive at the poles of the magnet. The bridging armature on the carrier might be a continuous shell or tube of magnetic material instead of rings or bands coupled with the bar of magnetic material extending between them, but for the fact that, when carriers have bodies of transparent material the material transported in the carriers will be largely cut off from view, making it difficult to inspect the material for assorting or classification without removing it from the carrier. While the rings 76 and 77 and the connecting bar 78 as shown in Fig. 8 are illustrated as comprising a continuous element, the rings and connecting bar may be of separate elements joined together as a continuous magnetic circuit.

Referring to Fig. 6, it will be observed that the magnets 70 and 71 have their poles spaced at different distances longitudinally of the guideway 10. It will further be observed that the wider pole spacing is employed for the magnet 70 and the narrower spacing is employed for the succeeding magnet 71 in the direction of travel of the carrier. This illustrates the preferred arrangement of the magnets in a system employing two or more branch tubes. That is, the magnets are arranged so that the widest spacing occurs first along the guideway and the spacing is decreased at each of the succeeding branch tubes in the direction of travel of the carrier. When the poles are spaced in this manner, carriers intended to be discharged at a predetermined branch along the guideway, beyond the first branch, the rings on the carrier, being spaced at the proper distance to bridge the poles of the magnet at such branch, would be of insufficient length to bridge the poles of any of the preceding magnets. Accordingly, none of the magnets will be sufficiently influenced by the passage of the carrier to start the corresponding relay tube until the carrier has reached the magnet having its poles spaced corresponding to the band spacing on the carrier.

Referring to Fig. 7, the preferred form of the magnetic poles is illustrated. The bar 70 of the magnets terminates in the form of loops or rings 78 at their poles which are arranged to surround the carrier tube 10. The width of the rings formed at the poles of the magnets, as shown in Fig. 6, are preferably of substantially the same width as the rings on the carrier. The loop formation at the poles of the magnet entirely surrounds the carrier and acts to decrease the effective air gap between the poles and the bands, which increases the sensitiveness of the combination, or in other words, increases the ability of the magnet to detect the presence of a carrier designated to be diverted from the main guideway at that point. With this arrangement it would be possible by a delicate adjustment of the cooperating device to operate a system without regard to whether the increase or decrease of the spacing of the magnetic poles is arranged in any definite order. This is because the coupling bar 75

between the rings on the carrier would not form a sufficiently effective bridge in passing the poles of a magnet having a spacing such that the rings on the carrier would extend beyond the poles.

5 Figs. 9 and 10 show another embodiment in which selectivity is accomplished by the use of only one magnet. This arrangement comprises a magnet 81 disposed with its poles transversely of the carrier guideway 10. The carrier 16 instead of being provided with spaced bands of magnetic material is provided with spaced coupling coils 82 and 83 joined together in series. A pick-up coil or inductance 84 is arranged to surround the carrier tube 10 and spaced from the magnet 81 at a distance corresponding to the coupling coils 82 and 83 on the carrier. When the carrier passes this point a current will be induced into the coupling coil 82 due to its cutting lines of force between the poles of the magnet 81. 10 This current will also flow through the coil 83 in series with the former coil which will likewise cause a potential to be induced into the pickup or inductance 84. Selectivity is obtained by employing carriers having the coupling coils spaced at different distances and a corresponding spacing of the magnet and pick-up at the predetermined branches.

30 The inductance 84 is included in the bridge circuit of a relay tube 85 similar to those employed in connection with the foregoing embodiments and having a similar trigger operating characteristic. The potential induced into the coil 84 will be impressed upon the grid 86 of the relay to cause the relay to be triggered setting up a current between the cathode 87 and anode 88 of the tube in the manner described heretofore, operating the switch control solenoid 19. The tube will be quenched by the carrier engaging the cam 34 of the interrupting switch 33 after it has been switched into a branch tube. The magnet 81 may assume a form similar to that shown in Fig. 10, it being noted that no pick-up coils on the magnet are required in this connection.

45 From the foregoing description it will be apparent that a carrier dispatch system having relay controlled switching means to discharge carriers at intermediate points or branches therealong has been provided with devices of extreme sensitivity and rapidity of response and which can be effectively operated at high carrier speeds.

50 In addition a system has been devised employing control means of extreme simplicity and which require the minimum number of parts for efficient operation. In particular, it will be observed that a system has been provided in which electronic relays having trigger operating characteristics have been employed for controlling the operation of the switching or diverting mechanisms at the branch stations along the guideway.

65 While this invention has been shown in several forms, it will be obvious to those skilled in the art that it is not limited to these forms but is susceptible to various other changes and modifications without departing from the spirit thereof, and it is desired, therefore, that only such limitations shall be placed thereon as are imposed by the prior art or as are specifically set forth in the appended claims.

70 We claim:

1. A conveyor, a switching mechanism for said conveyor, a slow acting device for operating said switching mechanism, an electronic device responsive to a condition of short duration produced by articles being conveyed to initiate a

discharge therethrough, said latter device being of such a character as to sustain said discharge at a substantially constant value for a sufficient period to operate said slow acting device.

2. A main conveyor, a branch conveyor, arc discharge device actuated by a condition of short duration produced by articles being conveyed for connecting said main and branch conveyors and means independent of said condition for maintaining said arc discharge device active until said article passes into said branch conveyor.

3. A main conveyor, a branch conveyor, switch means for deflecting articles being conveyed from one conveyor to the other, an electronic device having a trigger operating characteristic for actuating said switch means, means responsive to a condition of short duration provided by said article in its travel in advance of the switching thereof for releasing said electronic device, and means controlled by the passage of an article beyond the switch for restoring said trigger device to its preoperated condition.

4. In a conveyor system, a guideway, carriers for traveling along said guideway, a relay embodying an electronic discharge device having a trigger operating characteristic, and capable of being started by predetermined potential, means responsive to the passage of a carrier by a certain point along the guideway for supplying the starting potential, and means acting independently of said starting potential for quenching said device after an interval of time has elapsed.

5. A main conveyor, a branch conveyor, switching means for deflecting articles being conveyed from one conveyor to the other, an electrostatically controlled arc discharge tube for actuating said switching means, means responsive to a condition of short duration produced by said article in advance of the switching point for producing a discharge in said tube, said discharge once started being maintained independently of said condition and means controlled by the carrier for interrupting the discharge after the switching function has been completed.

6. In a conveyor system, the combination of a guideway for providing a carrier path, carriers arranged to travel along said guideway, a thermionic relay capable of being started by predetermined potential and of continuing in operation independently of said starting potential, means for establishing a magnetic field at a point along the carrier path, means transported by the carriers for causing a fluctuation in the magnetic field as the carrier passes the same, a pick-up coil in the field energized by the fluctuation of said field for supplying a starting potential to said relay, and switch means for interrupting said relay after a period of time has elapsed.

7. In a conveyor system, the combination of a pneumatic tube, carriers for traveling along said tube, a relay embodying an electronic discharge device capable of being started by a predetermined potential and of continuing in operation independent of said starting potential, means for establishing a magnetic field at a point along the carrier path, magnetic material transported by certain of said carriers for causing a variation in the flux of the magnetic field as they pass said point in the carrier path, means responsive to said flux variation for supplying a starting potential to the electronic discharge device, and means for quenching said device when the carrier passes another point along the carrier path.

8. In a conveyor system, a guideway, carriers for traveling along said guideway, a thermionic

relay having a trigger operating characteristic, a starting circuit and a sustaining circuit for said relay, means in the starting circuit for impressing a starting potential on the relay when a carrier passes a certain point along the guideway, and means for interrupting the sustaining circuit when the carrier passes another point along the guideway.

9. In a carrier system, a guideway, carriers for the guideway, each of said carriers having elements of magnetic material thereon arranged to embrace a different longitudinal portion thereof for different carriers, a single magnet disposed adjacent to the guideway and arranged to selectively respond to only those carriers having elements thereon embracing a predetermined longitudinal portion of the carrier, and a relay associated with said magnet and arranged to be energized thereby when the magnet responds to a carrier.

10. In a carrier system, a guideway, a carrier, a single magnet located adjacent said guideway, the poles of said magnet having a loop formation at their ends encircling said guideway, said poles being spaced apart a predetermined amount longitudinally of said guideway, and inductance coils in the field of said magnet, an armature of magnetic material on the carrier extending longitudinally thereof, said armature being of just sufficient length to extend through the pole loops of the magnet and adapted to momentarily bridge said poles for modifying the field of the magnet as the carrier passes, a local circuit including said inductance coils and a relay in said circuit arranged to be operated by the current induced by the modification of said field.

11. In a carrier system, a guideway, a carrier, magnetic material of a predetermined length secured to the carrier, a magnet adjacent to the guideway having its poles spaced longitudinally of the guideway at a distance corresponding to the length of the magnetic material on the carrier, said magnet being adapted to have its poles momentarily bridged by said magnetic material as the carrier passes the magnet, inductances in the field of said magnet, a local circuit including said inductances, and a relay adapted to be energized by the potential set up in the inductances when the magnet is bridged.

12. In a carrier system, a guideway, a carrier, magnetic material of a predetermined length secured to the carrier, a magnet adjacent to the guideway having its poles spaced longitudinally of the guideway at a distance corresponding to the length of the magnetic material on the carrier, said magnet being adapted to have its poles momentarily bridged by said magnetic material as the carrier passes the magnet, inductances in the field of said magnet, a local circuit including said inductances, an electronic relay having a trigger operated characteristic adapted to be started by the potential set up in the inductances when the magnet is bridged, and means for stopping the relay after a period of time has elapsed.

13. In a carrier system, a guideway, a carrier, a pair of bands of magnetic material spaced at predetermined distances on the carrier, said bands being coupled by magnetic material extending between them and partially around the carrier, a magnet adjacent the guideway having its poles spaced longitudinally of the guideway at a distance corresponding to the bands on the carrier, said magnet being adapted to have its poles momentarily bridged by said connected

bands as the carrier passes the magnet, inductances in the field of said magnet, and a relay adapted to be energized by the potential set up in the inductances when the magnet is bridged.

14. In a carrier system, a main guideway having a plurality of discharge points therealong, carriers for the system including carriers designated for each of the discharge points, a single magnet in advance of each of the points having its poles disposed adjacent the guideway and spaced apart longitudinally thereof, the poles of said magnets being spaced differently at each discharge point, each of said carriers being provided with a longitudinally extending armature of a length suitable for momentarily bridging the poles of the magnet corresponding to the point at which it is designated to be discharged, a switching device at the respective discharge points, a local circuit coupled to each magnet, a local operating relay for each switching device arranged to be energized by the potential induced in the local circuit when the poles of the magnet to which it is coupled are bridged.

15. In a carrier system, a main guideway having a plurality of branch guideways leading therefrom, carriers for the system including carriers designated for each of the branches, a magnet in advance of each of the branches having its poles spaced longitudinally of the guideway, the poles of said magnets being spaced at a progressively less distance apart in the direction of travel of the carriers, said carriers being provided with armatures suitable for momentarily bridging the poles of the magnet corresponding to the branch for which they are designated, whereby carriers designated for branches beyond the first branch will not bridge the magnets reached before the magnet corresponding to the branch for which the carrier is designated, a switching device at the entrance of the respective branches, a local circuit coupled to each of the branch magnets, a local operating relay for each of the respective switching devices arranged to be energized by the potential induced in the local circuit when the poles of the magnet to which it is coupled are bridged.

16. In a carrier system, carriers, a guideway for the carriers comprising a pneumatic tube having a branch leading therefrom, a switching device normally in inoperative position but movable into operative position to deflect carriers into the branch tube, means operative as a carrier passes one point along the guideway to move the switching device into operative position and means operative as the carrier passes another point to restore the switching device to normal position, said latter means being disposed entirely externally of the tube.

17. In a carrier system, carriers, a guideway for the carriers comprising a pneumatic tube having a branch leading therefrom, a switching device normally in inoperative position but movable into operative position to deflect carriers into the branch tube, means to move the switching device into operative position, and means operative as the carrier passes a point along the guideway to restore the switching device to normal position, said latter means being disposed entirely externally of the tube.

18. In a carrier system, carriers, a guideway for the carriers comprising a pneumatic tube having a branch leading therefrom, a switching device normally in inoperative position but movable into operative position to deflect carriers into the branch tube, a local controlling circuit

for operating the switching device, means to complete the circuit as a carrier passes one point along the guideway and means to interrupt the circuit as the carrier passes another point along the guideway, said latter means being disposed entirely externally of the tube.

19. A carrier system according to claim 18 in which both the circuit completing and interrupting means are disposed entirely externally of the tube.

20. A pneumatic carrier system, carriers, a guideway for the carriers comprising a main pneumatic tube having one or more branch tubes leading therefrom, means associated with each of the branch tubes to divert carriers from the main tube thereinto, said means being controlled by an electronic discharge tube, said discharge tubes being started into operation by means actuated when a carrier passes one point along the guideway, said tube being interrupted by means externally of the tube when the carrier passes another point.

21. In a pneumatic carrier system, carriers, a guideway for the carriers having one or more branches leading therefrom, means associated with each branch to divert carriers thereinto from the main guideway, said means being controlled by first and second electronic discharge tubes, said first discharge tube being started into operation by means actuated when a carrier passes one point along the guideway, and said second tube being started when the carrier passes another point along the guideway, and means actuated by the second tube to extinguish the first tube as soon as the second starts.

22. A pneumatic carrier system according to claim 21 in which one electronic discharge tube operates to move the diverting means to switching position and the other electronic discharge tube operates to return the same to normal.

23. In a pneumatic carrier system, carriers, a guideway for the carriers having one or more branches leading therefrom, means associated with each branch to divert carriers thereinto from the main guideway, said means being controlled by first and second electronic discharge tubes, said first tube being started into operation by means actuated when the carrier passes one point along the guideway, said second tube being started when the carrier passes another point along the guideway, means actuated by the second tube to extinguish the first as soon as the second tube starts, and automatic means to subsequently extinguish the second tube.

24. In a pneumatic carrier system, carriers, a guideway for the carriers having one or more branches leading therefrom, means associated with each branch to divert carriers thereinto from the main guideway, said means being controlled by first and second electronic discharge tubes, said first discharge tube being started into operation by means actuated when a carrier passes one point along the guideway, said second tube being started when the carrier passes another point along the guideway, and means actuated by each tube as soon as it starts to extinguish the other tube.

25. In a pneumatic carrier system, carriers, a guideway for the carriers having one or more branches leading therefrom, means associated with each branch to divert carriers thereinto from the main guideway, said means being controlled by first and second electronic discharge tubes, said tubes being provided with alternate circuit arrangements, one of said circuit arrange-

ments providing for the first tube to be started into operation by means actuated when a carrier passes one point along the guideway, and for the second tube to be started when the carrier passes another point along the guideway and means actuated by each tube as soon as it starts to extinguish the other tube, said second circuit arrangement providing for the tubes to be started in a manner similar to the first arrangement, and providing means actuated by the second tube as soon as it starts to extinguish the first tube, and automatic means to subsequently extinguish the second tube, and switching means provided for switching from one of said circuits to the other as desired.

26. In a carrier system, a guideway, a carrier, coupling coils on the carrier disposed in a predetermined spaced relation along the body of the carrier, said coils being connected together in parallel, a magnetic field at a point along the guideway and inductance surrounding the guideway and spaced longitudinally thereof from the field at a distance corresponding to the spacing of the coupling coils on the carrier, a local circuit including said inductance, a relay energized by the current set up in said inductance as the coupling coils on the carrier pass simultaneously through said field and said inductance, and means to deenergize said relay after a period of time has elapsed.

27. In a carrier system, a guideway having a plurality of discharge outlets therealong, carriers adapted to travel along the guideway, said carriers having elements of magnetic material thereon embracing different longitudinal portions of the carrier according to the outlet at which it is designated to be discharged, a single magnet disposed adjacent to the guideway in advance of each discharge outlet and arranged to selectively respond to the carriers designated for that outlet, a switching device at the respective discharge outlets, a local circuit coupled to each magnet, a local relay for each switching device arranged to be energized by the potential induced in the local circuit when the magnet responds to a carrier.

28. In a carrier system, a guideway, a carrier, a plurality of bands of magnetic material spaced at predetermined distances apart on the carrier, magnetic fields arranged at corresponding distances apart on the guideway and adapted to be simultaneously modified by the bands on the carrier, a local circuit, an arc discharge tube relay corresponding to each of the magnetic fields and having a grid arranged to be charged by the potential induced by the modification of said magnetic fields for conditioning the relay for discharge, said relays being arranged with their discharge circuits in series so that said local circuit is completed through the discharge path of all of the tubes, whereby none of said relays are energized except when all are energized so that the condition of said local circuit is not disturbed except when all of said relays become energized.

29. In a carrier system, a guideway, a carrier, a plurality of bands of magnetic material spaced at predetermined distances apart on the carrier, magnetic fields arranged at corresponding distances apart on the guideway and adapted to be simultaneously modified by the bands on the carrier, a local circuit combination, a relay in said circuit combination corresponding to each of said magnetic fields, each of said relays comprising an electronic discharge tube having a trigger operating characteristic, each of said tubes being

provided with an independent input circuit for supplying a starting potential to the tube, said input circuit being separately supplied with a starting potential by the modification of the respective magnetic fields, said tubes having their discharge circuits connected in series in said local circuit combination so as to provide a plurality of series circuit closing means in said circuit, said local circuit combination being characterized by the fact that the failure of one of the said tubes to discharge prevents all of them from discharging, so that the circuit closing means in said local circuit combination will not be disturbed except when all of said tubes are simultaneously started.

30. In a conveyor system for conveying articles,

article selective means for controlling the path of travel of articles through the system comprising a slow acting electrically operated device, current controlling means in circuit therewith for operating the same, and means disposed in position to selectively respond to the passage of certain articles for operating said current controlling means, said latter means embodying an electronic device for supplying current to the slow acting device, said electronic device being maintained at a substantially constant current output level for a sufficient time to complete the operation of said slow acting device.
